UNITED STATES PATENT OFFICE

2,576,325

BRUSH AND SCRAPER UNIT

Vernon D. Wood, Los Angeles, Calif.

Application August 6, 1948, Serial No. 42,975

3 Claims. (Cl. 15—111)

1

This invention relates, in general, to household scouring brushes, but more particularly to and has for an object the provision of a combined brush and scraper specially adapted for cleaning pots, pans, and other utensils as well as surfaces in or about a kitchen sink, wash basin, or otherwise.

To such end it is an object to employ a small and economical more or less conventional brush of light weight which is usually formed with the bristles held on a twisted wire frame bent into a loop with the ends attachable to a suitable handle, and a scraper attached to the device in a position between the bristles and the handle and either permanently or detachably held for use on the brush frame.

Another object is to preferably but not necessarily form the scraper of a single piece of sheet metal having an attaching portion conforming in contour and affixed to the brush frame and a forwardly extended scraper blade disposed in an inclined blade so as to overlie but be suitably spaced from the brush body that it may be conveniently used when the brush is held flatwise and thrust forwardly for scraping surfaces free of clinging matter, the reversal of the brush so that the scraper will be uppermost, then permitting the use of the opposite side of the brush from the scraper for scouring and cleaning the scraped surface by saponification or through the use of any desired detergent.

The form and character of the particular type of brush and scraper hereinafter shown and described readily lend themselves to the combination in a single unit for the dual results mentioned but the invention is not necessarily limited to any particular type of brush and scraper.

The accompanying drawing shows a preferred embodiment of the invention, subject to modification, within the scope of the appended claims, without departing from the spirit thereof. In the drawing:

Fig. 1 is a perspective view of the preferred form of brush embodying my invention;

Fig. 2 is a cross-sectional view of the same on line 2—2 of Fig. 1;

Fig. 3 is a fragmentary top plan view of the same;

Fig. 4 is a cross-sectional view on line 2—2 of Fig. 1, showing a modified form of scraper attachment as applied to the brush frame;

Fig. 5 is a view of another form of scraper attachment shown as a fragmentary side elevation;

Fig. 6 is a cross-sectional view of the same on line 6—6 of Fig. 5;

2

Fig. 7 is a fragmentary, bottom plan view of the brush showing a slightly modified means for attaching the scraper body to the brush frame; and

Fig. 8 is a perspective view showing means for attaching the scraper to the brush which is slightly different from the structure of Fig. 7.

A device embodying the mentioned and illustrated characteristics includes a more or less conventional type of brush B formed with its bristles arranged in a loop and frictionally held on a twisted wire frame F with a central loop 1 and terminal portions twisted together to form a receiving stem 2 for an applied handle H, intermediate sections 3, 3, leading from opposite points on loop 1 to stem 2 and being disposed between the stem and loop to form an acute angle therebetween.

A scraper S is affixed to the intermediate portions 3, 3 between brush B and handle H and is preferably formed of a single piece of sheet metal so contoured as to tightly fit over the intermediate section of the frame. To such end said scraper has a body plate 4 with marginal portions 5, 5, bent around and clinched on the intermediate sections 3, 3 of the frame, and an elongated forwardly inclined blade 6 extended over a side of the brush B. Thus, one side of the device may be used for scraping surfaces while the other side may be used for scouring when the device is reversed in the hand of the user.

The form of brush described and best shown in Figs. 1, 2, and 3 is subject to modification in minor respects, one modified form being illustrated in Figs. 5 and 6, another in Fig. 4, and still another in Fig. 7. The form of brush shown in Fig. 7 is similar to that of Figs. 1, 2 and 3 except that instead of providing continuous marginal flanges 5 at the sides of the scraper body 4, a pair of ears 5', 5' are provided at points near the front and rear extremities on each side of the body and are adapted to be crimped around the portions 3, 3 of frame F.

The type of device shown in Figs. 5 and 6 differs from that of Fig. 1, only in respect to the form and manner of attaching the scraper to the frame F. In this form the scraper S comprises two companion members constituting a body 4' with a scraper blade 6' integral therewith and an attachable base 7 secured to the body as by means of a stud 8 fixed to and depending from body 4' and passing through base 7 and a nut 9 threaded onto said stud for detachably holding the scraper S on the brush frame F.

Member 7 has upturned lateral flanges 10, 10

which frictionally fit the inner surfaces of similar flanges 11, 11 formed on body 4', so that when secured together by nut 9 and stud 8 the intermediate portions 3, 3 of brush frame F will be enclosed therein between the brush B and handle H.

As shown in Fig. 8, the two members of the scraper body shown in Fig. 7 may be frictionally held together by so forming the flanges of the body members that they will snap into attached position, one upon the other, by reason of a tension of the flanges, and may be separated by the employment of a suitable tool. In this instance, the stud 8 and nut 9 would, of course, be omitted, thereby simplifying the structure.

Fig. 4 illustrates a type of scraper body different from those of Figs. 2 and 6 which, as in Fig. 2, requires only a single integral scraper part and has long lateral flanges 5a, 5a overlying the sections 3, 3 of the frame F while the body 4a is spot welded at points 12, 12 to frame sections 3, 3 for permanently securing the scraper attachment to the brush.

In Fig. 7, the ears 5', 5' are substituted for the long marginal portions 5 of the scraper body and may be bent and crimped over the frame sections 3, 3 in a manner similar to the formation of the portions 5 of Figs. 1 and 2.

It is important that scraper blade 6 be disposed in an inclined plane forwardly of handle H and the scraper body so that when the brush is held by a user with the scraper downmost it is effective for removing attached accumulations of matter from the bottoms of pots, pans, and other utensils when the unit is urged forwardly with the leading edge of the scraper in contact with the surface to be cleaned.

Following completion of a scraping operation the device is turned so that the brush is downmost and becomes effective through the use of a suitable detergent for thoroughly scouring and cleaning the surface.

It is of course desirable in the production of a device of the character herein described to provide a structure which is of minimum cost to the user, maximum durability and efficiency, and sanitary. To such end it has been sought in the design of the instant cleaning unit to meet all such requirements and, particularly, to eliminate all possibility of unsanitary conditions by the absence of pockets or traps which would retain particles of decaying matter and thereby occasion undesirability while in or out of use.

In all forms of the unit herein shown and described the body of the scraper attachment encloses the intermediate sections 3, 3 and lends attractiveness as well as added utility and extraordinary sanitary features to the implement.

It will be understood that while the disclosed scraper attachment is particularly designed for use on one form of brush now in general use, it is apparent that the invention may be likewise applied to brushes of other forms with but slight modification of minor details and with no radical

departures from the preferred structure herein shown.

I claim:

5 1. In combination, a brush having a twisted wire frame formed with a forward loop portion, relatively inclined and converging intermediate portions and substantially straight and contiguous rear portions, a handle on said straight portions, tufted bristles held on said loop; and a 10 scraper having a body secured to the intermediate portions of the frame, and a blade extended forwardly over the bristles and disposed in a plane inclined relative to the plane of the loop for selective use when the device is disposed for 15 engaging said blade with a surface to be cleaned.

2. In combination, a brush having a twisted wire frame formed with a forward loop portion, relatively inclined and converging intermediate portions and substantially straight and contiguous rear portions, a handle on said straight portions, tufted bristles held on said loop; and a 20 scraper having a body secured to the intermediate portions of the frame, and a blade extended forwardly over the bristles and disposed in a plane inclined relative to the plane of the loop for selective use when the device is disposed for 25 engaging said blade with a surface to be cleaned, said scraper body having marginal portions bent over the intermediate frame portions for securing the scraper to the frame.

30 3. In combination, a brush having a twisted wire frame formed with a forward loop portion, relatively inclined and converging intermediate portions and substantially straight and contiguous rear portions, a handle on said straight portions, tufted bristles held on said loop; and a scraper having a body secured to the intermediate portions of the frame, and a blade extended forwardly over the bristles and disposed in a plane inclined relative to the plane of the loop for selective use when the device is disposed for 35 engaging said blade with a surface to be cleaned, said scraper body having marginal portions bent over the intermediate frame portions for securing the scraper to the frame.

40 4. In combination, a brush having a twisted wire frame formed with a forward loop portion, relatively inclined and converging intermediate portions and substantially straight and contiguous rear portions, a handle on said straight portions, tufted bristles held on said loop; and a scraper having a body secured to the intermediate portions of the frame, and a blade extended forwardly over the bristles and disposed in a plane inclined relative to the plane of the loop for selective use when the device is disposed for 45 engaging said blade with a surface to be cleaned, said scraper body including marginal portions formed to embrace the intermediate portions of the frame.
